United States Patent Office.

LUMAN L. CHAPMAN, OF PHILADELPHIA, PENNSYLVANIA.

Design No. 3,186, dated September 1, 1868.

DESIGN FOR A CORSET.

The Schedule referred to in these Letters Patent and making part of the same.

TO ALL WHOM IT MAY CONCERN:

Be it known that I, LUMAN L. CHAPMAN, of the city of Philadelphia, in the State of Pennsylvania, have invented or produced a new and original Design for a Lady's Corset; and I do hereby declare that the following is a full and exact description of the same, reference being had to the accompanying drawings, making a part of this specification, and to the letters of reference marked thereon.

My design relates to the puff-and-shoulder-brace corset, and consists in the peculiar form of the lower part of the same, as shown in the drawing.

What I claim as my invention, and desire to secure by Letters Patent, is—

The design for a corset, herein set forth and shown.

LUMAN L. CHAPMAN.
